UNITED STATES PATENT OFFICE.

EDWIN F. GUTH, OF ST. LOUIS, MISSOURI, ASSIGNOR TO ST. LOUIS BRASS MANUFACTURING COMPANY, OF ST. LOUIS, MISSOURI, A CORPORATION OF MISSOURI.

LIGHTING-FIXTURE.

1,248,849.

Specification of Letters Patent.

Patented Dec. 4, 1917.

Application filed January 15, 1917. Serial No. 142,397.

To all whom it may concern:

Be it known that I, EDWIN F. GUTH, a citizen of the United States of America, residing at the city of St. Louis, State of Missouri, have invented a certain new and useful Lighting-Fixture, of which the following is such a full, clear, and exact description as will enable anyone skilled in the art to which it appertains to make and 10 use the same, reference being had to the accompanying drawings, forming part of this specification.

My invention relates to improved means for supporting light shields, such as globes, 15 bowls or shades, in operative relation with the other parts of a lighting fixture. Although holding means constructed in accordance with my invention is applicable to many common forms of light shields, it is 20 particularly advantageous for use in supporting bowls whose greatest diameter is below the top of the bowl to which the supporting means is applied, and which therefore cannot pass through a closed supporting ring. And it is one of the principal objects of my invention to provide a cheap, 25 efficient and easily applied means for holding such bowls in proper position in the fixture, a further object being to so arrange 30 the holding means that it serves as a hinged support for the bowl, whereby one side of the bowl may be dropped down from the fixture and access had to the interior of the fixture for cleaning the same and the replacement 35 of the lamp. Other objects and advantages of my invention will appear from the following more detailed description.

In the accompanying drawings, which illustrate my invention, Figure 1 is a cross- 40 section of a fixture with the parts in assembled and normal relation; Fig. 2 is a side elevation showing the fixture with the bowl turned downward on its hinged support and in what may be termed its "dropped down" 45 position; Figs. 3 and 4 illustrate means for attaching the holder to the canopy or main support at a point preferably opposite the hinged portion of the holder; Fig. 5 is a top plan view of the holder.

1 represents the main supporting ring, 50 which may be the canopy in a ceiling type of fixture, and 2 a bowl or shade inclosing the lamp 3. The bowl is provided with the usual lip, as shown. The holder 4 is in the

form of an open ring, preferably of resilient 55 material, such as spring wire, and the ends of this ring are extended and turned downwardly to form hooks 5 which enter and engage with the opening 6 in the canopy. The holder, at a point preferably opposite the 60 hooked portions, is provided with an extension 7 adapted to enter a downwardly extending opening 8 in the canopy, and to be suitably held in such opening.

In assembling the fixture the ring holder 65 is applied around the bowl beneath the lip by spreading, if necessary, and its hooked ends 5 are held sufficiently close together to permit both to enter the opening 6. The width of this opening is so restricted that 70 when the hooks have been inserted they cannot spread apart sufficiently to permit the lip of the bowl to pass through the holder, and the bowl is therefore securely supported 75 on the canopy, and by engaging the extension 7 with the canopy the bowl is brought into its normal position. The extension 7 may be engaged with the canopy in any suitable manner, such as by providing the canopy with the form of notch shown in Fig. 3, 80 or by providing it with a sliding bar 9, such as is shown in Fig. 5, which is adapted to pass under the extension 7.

It will be noted that the holder described 85 forms a very cheap and simple means of supporting the bowl, and at the same time forms a suitable hinge whereby access may be had to the interior of the fixture without entirely separating the bowl therefrom. The form of hinge provided by this holder 90 is an improvement over the pivoted hinge which has heretofore been generally used for attaching the bowl supporting ring to the canopy, and which usually gets out of order or is broken after a short period of 95 service.

I am aware that spring rings have heretofore been employed for supporting light shields, but no constructions with which I am acquainted have the characteristics and 100 advantages of my invention.

Modifications may be made in the form 105 of holder herein described without departing from the essential characteristics thereof, and I therefore do not intend that the scope of my invention be limited otherwise than by the appended claims.

Having fully described my invention,

what I claim as new and desire to secure by Letters Patent of the United States is:

1. In a lighting fixture, the combination of a light shield, a main support therefor, 5 an open holder ring adapted to be placed around the shield and having its ends provided with hooks, and means on the main support for engaging with said hooks whereby the shield is supported in hinged relation with the main support.
2. In a lighting fixture, the combination of a light shield, a main support therefor, 15 an open holder ring adapted to be placed around the shield and having its ends provided with hooks, and means on the main support for engaging with said hooks whereby the holder is supported in hinged relation with the main support and is maintained in position on the shield.
- 20 3. A holder for globes, bowls and the like comprising a one-piece open ring having a hook formed on each end, said hooks extending substantially at right angles to the plane of the ring, and a supporting extension spaced from the hooks.
- 25 4. In a lighting fixture, the combination of a light shield, a support therefor, a holder ring adapted to engage with the shield, said ring having a bent portion for engagement 30 with the main support, and means on the main support coöoperating with said bent

portion to form a hinge capable of supporting the shield in a dropped down position with reference to the support.

5. In a lighting fixture, the combination 35 of a light shield, a support therefor, a holder ring adapted to engage with the shield, said ring having a bent portion for engagement with the main support, means on the main support coöoperating with said bended portion to form a hinge capable of supporting the shield in a dropped down position with reference to the support, and additional means for connecting the ring to the support, said means being engageable after the 45 parts forming the hinge have been engaged.

6. In a lighting fixture, the combination 50 of a light shield, a main support therefor, an open holder ring adapted to be placed around the shield and having its ends provided with hooks formed at an angle to the plane of the ring, the main support being provided with means to engage with said hooks to form a hinge, and an extension on the ring and spaced from the hooks, said 55 main support also being provided with a recess opening downwardly to receive the said extension.

In testimony whereof, I have hereunto set my hand and affixed my seal.

EDWIN F. GUTH. [L.S.]
